DESIGN FOR A CASING FOR POLISHING MACHINES

Nathaniel N. Okun, New York, N. Y.

Application August 28, 1936, Serial No. 64,619

Term of patent 7 years

To all whom it may concern:

Be it known that I, Nathaniel N. Okun, a citizen of the United States, residing in Manhattan, in the city, county, and State of New York, have invented a new, original, and ornamental Design for a Casing for Polishing Machines, of which the following is a specification, reference being had to the accompanying drawing, forming a part thereof, in which:—

Fig. 1 is a side elevational view of my casing for polishing machines embodying my new design, and

Fig. 2 is a plan view thereof.

I claim:—

The ornamental design for a casing for polishing machines, as shown.

NATHANIEL N. OKUN.
